C. SCHOONMAKER,
PORTABLE ELECTRIC HEATER,
APPLICATION FILED FEB. 20, 1918.

1,292,094.

Patented Jan. 21, 1919.

UNITED STATES PATENT OFFICE.

CARL SCHOONMAKER, OF NEW YORK, N. Y.

PORTABLE ELECTRIC HEATER.

1,292,094.

Specification of Letters Patent. Patented Jan. 21, 1919.

Application filed February 20, 1918. Serial No. 218,235.

To all whom it may concern:

Be it known that I, CARL SCHOONMAKER, a citizen of the United States, residing in the city of New York, county of New York, 5 and State of New York, have invented certain new and useful Improvements in Portable Electric Heaters, of which the following is a full, clear, and exact specification.

10 My invention relates to electric heaters and refers particularly to portable electric heaters.

The object of my invention is an electric heater of such a size, shape and arrangement of parts that it may be readily and safely carried in a receptacle, such as a trunk or bag, and may be readily attached to an electric light socket without disconnecting, or removing, the glass or porcelain 15 shape usually carried thereby.

In order that an electric heater may be suitable for personal transportation, as described above, it must be compact, light in weight, so arranged that the delicate parts 25 thereof will be protected from breakage, must overcome the necessity of the ordinary insulated wires and must protect the shade from breakage due to the intense heat of the heated wires.

30 Compactness and lightness are essential not only in order to facilitate the carrying thereof, but are necessary when it is desirous of introducing the heater into an electric light socket carrying a shade, the latter 35 being usually of limited size, and where the heater is suspended during its use without any support beneath it upon which it may rest.

As the heater is liable to sudden jars and 40 the impact of other articles when packed into a carrying receptacle, it is essential that the more delicate portions, as for instance the resistant wires, be protected in order to prevent dislocation and breakage.

If the heater is compact in form, it will necessarily be within the usual glass, or porcelain, shade and means must be employed whereby the shade will not be broken by the heat emanating from the heater.

45 Further, the heater must be easy of construction, economical in cost and as free as possible from damage due to rough usage.

The device of my invention accomplishes all of the above desirable results and overcomes the objectionable features of the 55 present known heaters.

In the particular form of my device shown in the accompanying drawings, similar parts are designated by similar numerals.

Figure 1 is a vertical cross-section of one form of my device.

Fig. 2 is a cross-section through the line 2-2 of Fig. 1.

Fig. 3 is a cross-section through the line 65 3-3 of Fig. 1.

Fig. 4 is a modified form of the lower portion of the shell of the device.

The particular form of my device, as illustrated comprises an exterior shell composed 70 of the upper member 5 and the lower member 6 attached thereto by the flange joint 7. The lower member 6 has a series of openings 8, 8 to allow of the exit of the heat from within the shell. The upper portion of the 75 upper member 5 is carried by the electric non-conductor 9, having the exterior thread 10, capable of engagement with the interior thread 11 of the ordinary standard electric light socket 12. The interior of the member 80 5 is covered with asbestos 13. The upper face of the member 9 carries the downwardly extended electric conductor plate 14, the lower portion of which is bent for purposes described later. The plate 14 extends 85 through the opening 14^A of the member 9.

The device for carrying the heating wires comprises a hollow porcelain member having extended arms 15, 15 upon the outer face of which is a spiral recess 16. A downwardly 90 extended electric conductor plate 17, having a recess in its lower portion, is attached to the center of the member 9 by means of the copper screw 18, the latter being capable of abutment upon the electric circuit point 95 of the socket 12. The plate 17 extends through the opening 17^A of the member 9. The head 15^A of the member 15 carries the upwardly extended electric conductor plate 20 having a projection in its upper portion 100 to holdably engage with the recess of the plate 17. The head 15^A also carries the upwardly extended electric conductor plate 21, having a projection in its upper portion to

holdably engage with the recess of the plate 14.

The plate 20 is connected by means of the wire 22 to the coiled resistance wire 23 which is placed within the recess 16 of the member 15, the coiled wire 23 being extended into the wire 24 connected to the plate 21. An ordinary shade 26 is suspended by means of the shade support 26A.

10 Fig. 4 illustrates a modified form of the lower shell of Fig. 1, comprising a series of wires 27, 27 so arranged as to act as a protective guard for the interior of the device. This modified form of the lower shell can 15 be fixedly attached to the upper shell, or movably attached thereto by the resilient action of the wires 27, 27.

It is evident that the shell 5 may be composed of a non-conductor of heat instead of 20 being covered by such non-conductor as shown; that the member 15 may be of suitable composition other than porcelain; that the arrangement of the wire 23 may be different from that shown and the lower shell 25 6 may be of any suitable protective material and shape.

I do not limit myself to the particular size, shape, number or arrangement of parts as shown and described, all of which may be

varied without going beyond the scope of my invention as described and claimed.

What I claim is:—

1. A portable electric heater comprising an upper non-heat conducting shell, an exterior thread upon the upper portion of the upper shell capable of being threaded into an electric light socket, a lower foraminous shell capable of engagement with the upper shell, a resistance wire within the chamber formed by the two shells and means whereby the insertion of the upper shell into a light socket will connect the resistance wire with the electric wires of the light socket. 35

2. A portable electric heater comprising an upper imperforate non-heat conducting shell, an exterior thread upon the upper portion of the upper shell capable of being threaded into an electric light socket, a lower foraminous shell capable of engagement with the upper shell, an insulating carrying body 40 50 within the chamber formed by the two shells, a resistance wire carried by the carrying body, and means whereby the insertion of the upper shell into the light socket will connect the resistance wire with the electric 55 wires of the light socket.

CARL SCHOONMAKER.
